(57) **CLAIM**

The ornamental design for a hose nozzle, as shown and described.

DESCRIPTION

FIG. 1 is an elevated perspective view of a hose nozzle, according to our new design;

FIG. 2 is a front view of the hose nozzle shown in FIG. 1;

FIG. 3 is a rear view of the hose nozzle shown in FIG. 1;

FIG. 4 is a top view of the hose nozzle shown in FIG. 1;

FIG. 5 is a bottom view of the hose nozzle shown in FIG. 1;

FIG. 6 is a first side view of the hose nozzle shown in FIG. 1; and,

FIG. 7 is a second side view of the hose nozzle shown in FIG. 1.

The portions shown in broken lines form no part of the claimed design. Regions surrounded by broken lines are also unclaimed.
